UNITED STATES PATENT OFFICE.

ALICE MARY ARGLES, OF WIMBLEDON, ENGLAND.

COIN-FREED MECHANISM FOR GOODS-DELIVERY MACHINES.

SPECIFICATION forming part of Letters Patent No. 678,153, dated July 9, 1901.

Application filed October 9, 1900. Serial No. 32,519. (No model.)

To all whom it may concern:

Be it known that I, ALICE MARY ARGLES, a subject of the Queen of Great Britain, residing at Overdale, Wimbledon, county of 5 Surrey, England, have invented certain new and useful Improvements in Coin - Freed Mechanism for Goods-Delivery Machines, of which the following is a specification.

The object of my invention is to provide a 10 means whereby when a number of compartments or appliances are arranged one above the other or side by side or otherwise it is only necessary that one coin-slot (and, if required, one push-rod) be provided to actuate 15 the mechanism connected with each compartment or appliance in succession on the dropping in of a coin.

My invention will be clearly understood from the following description, aided by the 20 accompanying drawings, in which the several figures show one example of carrying my invention into practice.

Figure 1 is a plan of the mechanism affixed to a casing and in the inoperative position. 25 Fig. 2 is also a plan with the mechanism in an operative position. Fig. 3 is an elevation of the mechanism with sufficient of the actual holding appliances to illustrate the invention. Fig. 4 is a side elevation of the coin-actuated 30 and goods-retaining mechanism, the coin being in position ready for actuation by the push-rod for releasing the second goods-retaining mechanism, the top goods-retaining mechanism having been released by the previously-inserted coin and held in the released 35 condition. Fig. 5 is a side view of the coin-actuated mechanism with the casing removed, the coin and mechanism being in the first operative position. Fig. 6 is a similar view with 40 the coin in the second operative position, a locking-lever having been lifted by the coin to allow of a further and full movement of the push-rod. Fig. 7 is a similar view to Figs. 5 and 6, the push-rod having been pushed 45 fully home for operating, through the medium of a pivoted rod and gravity-pawl, the goods-retaining mechanism, the coin having been discharged. Fig. 8 is a side elevation of the coin-actuated casing, showing the slot 50 in which the pin of the push-rod slides for actuating the pivoted rod. Fig. 9 is a side

elevation of the opposite side to that shown in Fig. 8.

For the purpose of my invention I will describe same as applied to a machine in which 55 newspapers, books, and the like are held by claws or levers upon brackets or shelves arranged one above the other—such as is described in my former British specifications, No. 7,268, dated April 6, 1899, and No. 333 60 of the year 1900; but it must be understood that my mechanism is applicable for all classes of apparatus where an article or goods to be delivered is contained within or held by appliances complete within themselves and arranged one above the other or in series for delivery at the bottom of the apparatus.

I attach in proximity to the ordinary coin-freeed mechanism—situate, say, at the upper part of the casing—a square or other shaped 70 rod *a*, this rod *a* extending from top to bottom of the casing and near the actuating mechanism. On this rod *a* I place a gravity-pawl *b*, having a projecting arm *c* and capable of movement up and down the rod *a*. The 75 projecting arm *c* of the gravity-pawl *b* also carries a lug *d* for resting on the projecting levers of the actuating mechanism, these being arranged superposed, as shown in Fig. 3. The rod *a* has an arm *e* and is controlled by a 80 spring *f* for return.

On the insertion of a coin into the coin-operating mechanism the same or the push-rod will press against the projecting arm *e* and move it and also the rod *a* around a short 85 distance, the projecting arm *c* of the pawl *b* also moving around and acting upon the projecting lever *g* of one of the actuating mechanisms, and so release the mechanism which is retaining the newspapers, books, or other 90 articles to be released, and on the coin or the push-rod *h*, or both, being pushed in a certain distance or after the operation the coin will be released and fall into the casing the coin-operated mechanism will be returned to its 95 normal position, and the rod *a* will also be returned under the action of its spring *f*, and by so doing and by reason of the actuating mechanism remaining in the releasing condition the pawl *b* will be free from the lever 100 *g* and will drop into the one next below, it being retained there by the lug *d* resting upon

the actuating-lever, the projecting arm *c* on the pawl *b* being in position for a fresh movement on the insertion of another coin, the operation continuing until the last mechanism 5 is reached, when the pawl *b* can be drawn up to the top, the compartments or appliances resupplied with goods, and the levers placed in position for locking the compartments.

In the construction shown in the drawings 10 the coin is dropped through a coin-slot in the casing and into a chute *j*, upon the bottom of which it rests and between a projecting pin *k* of a locking-lever *l* and the pin *m* of the push-rod *h*, the locking-lever *l* and the push-rod *h* 15 being arranged at the side of the coin-chute *j* for the pin of the push-rod to ride in slots of the coin-chute. On the coin being inserted and the push-rod *h* operated the coin will ride against the pin *k* of the locking-lever (see Fig. 20 5) and lift the locking-lever *l* clean of the push-rod extension *n*, so as to enable the push-rod to be pushed in far enough for its pin to operate the projecting arm *e* of the rod *a* and move said rod *a*, and with it the 25 pawl *b*, around, so that the arm *c* of the pawl *b* actuates the lever *g* for passing it under the arm *p*, which carries the pinned or other plate *q* for holding the newspapers or other articles upon a shelf or within a box until the 30 lever *g* comes under an opening in the arm *p*, when a spring will immediately cause the opening in the arm *p* to embrace the lever *g* and hold it in the position seen in Fig. 4, the arm *p* and plate *q* remaining in the release condition 35 for the articles to be removed. When the push-rod has traveled a sufficient distance to effect this releasing, the coin is released, the two actions occurring simultaneously. On the push-rod *h* being released, 40 the spring *f* draws back the arm *e* for returning the rod and pawl to their normal conditions, the pawl by this action becoming free from the lever *g* and falling onto the next lower lever into position for an operation on 45 that lever on a fresh coin being inserted in the coin-slot and the push-rod *h* reactivated. On the return of the push-rod *h*, assisted by its spring *r*, the locking-lever *l* will fall for its nose to be in the path of the push-rod extension *n* and so prevent the mechanism being 50 actuated without the insertion of a coin.

In the drawings I have shown a helical spring *f* for drawing the projecting arm *f* against a stop *s*; but any kind of spring can 55 be applied and may encircle the rod *a* for the purpose.

What I claim, and desire to secure by Letters Patent, is—

1. In a coin-free apparatus for goods-delivery machines, an operating-rod, means for actuating said rod; and a gravity-pawl sliding upon said rod for operating successively a series of separate goods-delivery devices, substantially as described.

65 2. In a coin-free apparatus for goods-delivery machines, a spring-actuated operating-

rod, a spring-actuated means for operating said rod, and means sliding downwardly upon said rod for operating successively a series of separate goods-delivery devices.

3. In a coin-free apparatus for goods-delivery machines, a spring-actuated operating-rod, spring-actuated means for operating said rod, and a gravity-pawl loosely mounted on said rod for actuating successively a series of 75 separate goods-delivery devices.

4. In a coin-free apparatus for goods-delivery machines, a gravity-pawl for operating successively a series of separate goods-delivery devices, a spring-actuated means for supporting and operating said pawl, and a push-rod for operating said spring-actuated means.

5. In a coin-free apparatus for goods-delivery machines, a gravity-pawl adapted to operate successively a series of separate goods-delivery devices, a spring-actuated rod for supporting and operating said pawl, and a push-rod for actuating said spring-actuated rod.

6. In a coin-free apparatus for goods-delivery machines, an operating-rod, a gravity-pawl carried thereby and provided with a lug, means for actuating said rod causing thereby the operation of the pawl, and means connected to said rod for returning the same to 95 its normal position.

7. In a coin-free apparatus for goods-delivery machines, a locking-lever released by the coin, an operating-rod, a gravity-pawl carried thereby, means for actuating said rod causing the operation of the pawl when the said lever is released, and means connected to said rod for returning the same to its normal position.

8. In a coin-free apparatus for goods-delivery machines, a locking-lever released by the coin, a spring-actuated operating-rod, a gravity-pawl carried thereby, and a spring-actuated means for operating said rod when said lever is released, and means connected to said rod for returning the same to its normal position.

9. In a coin-free apparatus for goods-delivery machines, a locking-lever released by the coin, an operating-rod, a gravity-pawl carried thereby and adapted to actuate successively a series of separate goods-delivery devices, a spring-actuated means for operating said rod when said lever is released, and means for returning said rod to its normal position.

10. In a coin-free apparatus for goods-delivery machines, a locking-lever released by the coin, an operating-rod, a gravity-pawl carried thereby and provided with a lug, a push-rod for actuating said rod when the lever is released, means for returning said push-rod to its normal position, and means for returning said operating-rod to its normal position.

11. In a coin-free apparatus for goods-delivery machines, an operating-rod, a pawl traveling thereon and adapted to operate at

- different points of its travel a separate goods-delivery device, means for operating said rod, and a push-rod for operating said means.
12. In a coin-freed apparatus for goods-delivery machines, an operating-rod, a pawl traveling thereon and adapted to operate at different points of its travel a separate goods-delivery device, a spring-actuated means for operating said rod, and a spring-actuated push-rod for operating said means.
13. In a coin-freed apparatus for goods-delivery machines, an operating-rod, a pawl traveling thereon and adapted to operate at different points of its travel a separate delivery device, means for operating said rod, a push-rod for operating said means, and a locking means released by a coin to permit of the operation of said push-rod.
14. In a coin-freed apparatus for goods-delivery machines, a traveling pawl for operating at different points of its travel a separate goods-delivery machine, an operating-rod for said pawl, operating means for said rod, and a locking-lever released by a coin to permit of the operation of said means.
15. In a coin-freed apparatus for goods-delivery machines, a gravity-pawl adapted to operate at different points of its travel a separate goods-delivery device, and a spring-actuated operating means therefor.
16. In a coin-freed apparatus for goods-delivery machines, a gravity-pawl adapted to operate at different points of its travel a separate goods-delivery device, operating means therefor, and a locking mechanism released by a coin to permit of the operation of said operating means.
17. In a coin-freed apparatus for goods-delivery machines, a gravity-pawl adapted to operate separate goods-delivery devices, and means for partially rotating said pawl at different points of its travel to cause the operation of the separate goods-delivery devices.
18. In a coin-freed apparatus for goods-delivery machines, a gravity-pawl adapted to operate separate goods-delivery devices, a rod for supporting and partially rotating said pawl at different points of its travel, and means for operating said rod.
19. In a coin-freed apparatus for goods-delivery machines, a gravity-pawl traveling in a vertical direction and adapted to operate separate goods-delivery devices, a rod for supporting and partially rotating said traveling pawl at different points of its travel, and means for operating said rod.
20. In a coin-freed apparatus for goods-delivery machines, a vertically-movable and partially-rotating gravity-pawl adapted to operate separate goods-delivery devices, a rod for supporting and partially rotating said traveling pawl at different points of its travel, means for operating said rod, and a locking mechanism released by a coin to permit of the operation of said means.
21. In a coin-freed apparatus for goods-delivery machines, a downwardly-moving and partially-rotating gravity-pawl for operating at different points of its travel a separate goods-delivery device, and means for partially rotating said pawl at different points of its travel.
22. In a coin-freed apparatus for goods-delivery machines, a downwardly-moving and partially-rotating pawl for operating at different points of its travel a separate goods-delivery device, supporting means for the said pawl, means for operating said supporting means for causing the partial rotation of said pawl, and a locking mechanism released by a coin to permit of the operation of said operating means.
23. In a coin-freed apparatus for goods-delivery machines, a gravity-operated means for actuating successively a series of separate goods-delivery devices, a support for operating said gravity means, and means for operating said support.
24. In a freed apparatus for goods-delivery machines, a gravity-operated means for actuating successively a series of separate goods-delivery devices, a spring-actuated support for operating said gravity means, and a spring-actuated means for operating said support.
